FLASHLIGHT CONSTRUCTION

Joshua Gordon Lippincott, Scarsdale, N. Y., assignor to Guth, Stern & Co., Inc., a corporation of New York

Application June 15, 1944, Serial No. 540,418

7 Claims. (Cl. 240—10.66)

1

This invention relates to portable flashlights and more particularly to hand or pocket flashlights of improved construction.

Among the objects of the invention is to generally improve flashlights of the character described which shall comprise few and simple parts that are readily assembled to form a rugged, compact yet neat and attractive appearing article, which assembly shall have the parts conveniently proportioned for use, which shall be inexpensive to manufacture, and which shall be practical and efficient to a high degree in use.

Other objects of the invention will in part be obvious and in part hereinafter pointed out. The invention accordingly consists of features of construction, combinations of elements, and arrangements of parts which will be indicated in the following claims.

In the accompanying drawing in which is shown an illustrative embodiment of this invention:

Fig. 1 is a sectionalized view taken longitudinally through a hand flashlight constructed with a toggle-like switch and "tulip" head embodying the invention.

Figs. 2 and 3 are enlarged cross-sectional views taken through fragmentary portions of the improved flashlight construction at lines 2—2 and 3—3, respectively, in Fig. 1.

Fig. 4 is a cross-sectional view taken on lines 4—4 in Fig. 3, and

Fig. 5 is a front elevational view of the improved flashlight showing the exterior construction.

Referring in detail to the drawing 10 denotes an improved toggle-like switch, "tulip" head, hand flashlight construction embodying the invention. As seen from Figs. 1 and 5, the flashlight construction 10 includes a tubular casing portion 11 formed with an integral closed bottom 11a and an enlarged bulbous hemispherical open end 11b. Said casing portion 11 preferably is made of sufficient length to house one or more electric dry cells 12 of conventional construction inwardly of said enlarged open end 11b as shown in Fig. 1. Said flashlight construction 10 also includes a bezel cap portion 13 secured to said open end 11b by suitable means, such as screw joint 14. The screw joint 14 may be formed with an interior thread 11c on the inner surface of the casing open end 11b engaging exterior threads 13a provided on the bezel cap portion 13. The exterior surface 13b of said cap portion 13 preferably is arcuate shaped forming a curved spherical outer surface portion aligning with the exterior

2

surface of the hemispherical open end 11b giving a "tulip" shape appearance to the flashlight head.

The exterior surface of the casing portion 11 below the enlarged open end 11b which houses the dry cells 12 may be formed with the spaced flutes 11d raised to extend longitudinally thereon and shown in Fig. 5 to provide efficient hand gripping means, the end of said casing portion 11 adjacent the closed bottom 11a being tapered as 10 at 11e to not only improve the casing portion 11 structurally but also with the flutes 11d to give the flashlight 10 a neat and attractive appearance.

The entire casing portion 11 and bezel cap portion 13 above described are each preferably molded of suitable plastic material of any well known composition that can be colored as desired and finished without machining to exact size and shape required. It has been found that by making 15 the body portion 11 and bezel cap portion 13 in a contrasting color combination, as for example, said body portion 11 in a high key shade, namely ivory, and the bezel cap portion 13 and a lever handle 15a of a toggle-like switch 15, hereinafter more fully described, in a low key shade, namely, bright red or some other contrasting color, a unique trimming is provided which lends itself to universal artistic appeal.

The bezel cap portion 13 has an inwardly extending flange 13c on the interior rim of which 30 may be seated a lens closure disc 16 as shown in Fig. 1. Abutting the peripheral portion of said disc 16, an outturned flange 17a of a metallic reflector 17 is positioned. The reflector 17 extends into the enlarged open end 11b of the casing portion 11 and carries a centralized screw shell portion 17b into which projects a base 18a of an incandescent lamp 18. The lamp base 18a has a central terminal contact 18b located to continuously press against a top center terminal 12a of dry cell battery 12.

The bezel cap portion 13 preferably may be made of a thicker stock than the body portion 11 to withstand rough handling and usage and the 45 rim of the flange 13c provides a sturdy supporting ledge for the reflector flange 17a as seen from Fig. 1.

The toggle-like switch 15 may comprise the lever handle 15a which is mounted to extend 50 through an opening 11f provided in the casing portion 11 at the junction of the battery compartment thereof and the structural portion of the enlarged bulbous open end 11b. The inner end 15b of said handle 15a is trunnioned by means of 55 integrally formed oppositely extending stub shafts

15c which extend down into open ended slots 11h of a boss 11g molded to extend from the interior side of the casing portion 11 along the rim of the opening 11f. Said boss 11g with said slotted construction provides bearings in which said stub shafts 15c are journalled.

The inner end 15b of lever handle 15a has a flattened surface 15d which is adapted to permit a tongue 19a terminating a connection strip or lead jumper 19 to be in an unflexed position when the circuit from the dry cell battery 12 is open or in "off" position, as shown in full lines in Fig. 1 and in Fig. 2. The handle portion 15a will then be swung in a direction extending away from the opening 11f. Said inner end of lever handle 15a also may be provided with a projection 15e which is located just beyond, that is, outside an axis of the lever handle 15a through the pivotting point thereof when in "off" or open switch position. Spaced from said projection 15e on the inner end of lever handle 15a opposite flattened surface 15d is a stop portion 15f which with said projection 15e retains the lever handle in closed circuit or "on" position with the tongue 19a flexed to electrically contact the reflector 17 as shown in Fig. 1 in dotted lines.

As seen from Fig. 1, when the lever handle 15a of toggle-like switch 15 is swung in between the "off" and "on" position the circuit will be closed but when said handle 15a is released it will return either to "off" position or swing to "on" position depending on whether the projection 15e is on one or the other side of the "off" position of the axis (dead line) of the lever handle 15a.

From the above described parts and assembly it is seen that the flashlight circuit passes from the center terminal 12a of the dry cell battery 12 to the center contact 18b of the lamp base 18a. The remaining portion of said circuit may include a metallic helical coil spring 23 seated within the closed casing bottom 11a having an end 23a contacting with container terminal 12b of the dry cell battery 12, an end 19b of the strip 19 opposite tongue 19a being interposed between said bottom 11a and spring end 23b to electrically contact the strip end 19b. The strip 19 thus electrically connecting with the battery container terminal 12b may be secured to the casing by suitable means such as rivet 22 for extending said strip 19 along the interior of the casing body 11 with said tongue 19a terminating above boss 11g. The tongue 19a on being flexed by the swinging of the handle 15a from a normal "off" position contacts the reflector 17 for completing the circuit through the screw base 18a of the lamp 18 in the well understood manner. If desired helical spring 23 may be integrally formed to terminate strip end 19b instead of being made as a separate element.

In order to anchor the strip 19 more firmly to the body 11, the tongue 19a is made by slitting the strip 19 on opposite sides of the tongue as at 19c and forming spaced attachment means with reversed bent spring end 19d. The latter not only can be sprung into position for firmly gripping over the lip rims of slots 11h but also extend into said slots 11h to bear against stub shafts 15c of the lever handles 15a as seen in Fig. 4.

With the parts made and assembled as described above and shown in the drawing, the practical utility of the invention becomes at once apparent. The flashlight 10 can be conveniently carried in the hand and the toggle switch 15 readily actuated by the thumb for either flashing the light by swinging the lever handle 15a partially up from the position shown in Fig. 1, 75

that is, so that the spring tongue 19a is either held deflected in closed circuit contact with the reflector 17, or swing by the lever handle fully to a self retain position with said tongue 19a in such circuit contact position as shown in Fig. 1, in dotted line position. To open the circuit the lever handle 15a is swung down permitting the tongue 19a to return back to the unflexed position shown in Fig. 1, full line position.

10 It is thus therefore seen that there is provided an improved flashlight in which the objects of the invention are achieved and which are well adapted to meet all conditions of practical use.

As various possible embodiments may be made 15 in the invention for use for different purposes and as various changes might be made in the embodiment above set forth, it is to be understood that all the above matters here set forth or shown in the accompanying drawing, are to be interpreted 20 as illustrative and not in a limiting sense.

Thus having described my invention, I claim as new and desire to secure by Letters Patent:

1. In a flashlight of the character described, a single molded plastic battery casing comprising an elongated tubular body of substantial uniform circular cross-section formed with a closed end bottom and a bulbous hollow hemispherical open end top opposite said bottom, a metallic strip jumper secured to extend lengthwise the interior side of said body and bottom to provide an electrical conductor for connecting with an under terminal of a dry cell battery housed in the casing, the end of said jumper at said open end top terminating in a toggle switch connecting part formed with an integral spring blade contact adapted to connect said battery in circuit, a riveted fastening means for rigidly securing said jumper at an inner part of the blade contact to said body, gripper attachment means provided on portion of the jumper end adjoining the blade contact at a spaced distance from said fastening means, an anchorage boss molded on an interior wall of the bulbous open end top for engaging with said gripper attachment means, and a toggle-like switch lever extending through the casing trunnioned on said boss for actuating said blade spring contact to deflect the latter in making and breaking a circuit connection.

2. In a flashlight of the character described, a construction as defined in claim 1 in which said anchorage boss has open ended slots to serve as bearings for trunnioning said lever therein, said gripper attachment means being constructed and arranged as a spring mounting integrally formed with said jumper portion projecting into said slot bearings to confine said trunnioned portions of said switch lever therein.

3. In a flashlight of the character described, a single molded plastic battery casing comprising an elongated tubular body of substantial uniform circular cross-section formed with a closed end bottom and a bulbous hollow hemispherical open end top opposite said bottom, a boss molded on an interior wall of the bulbous open end top having open-ended slot bearings, a toggle-like switch-lever extending through the casing having stub shafts journalled in said bearings to trunnion said lever on the boss, and an elongated metallic strip jumper having a battery contact at one end secured to extend lengthwise the interior side of said body with said battery contact at the bottom, the other end of said jumper being slotted to terminate in an integrally formed spring switch blade contact with adjoining gripper attachment means, and fastening means secured inwardly of

said blade contact for rigidly attaching said jumper to the body, an inner end of said lever being positioned to deflect the blade contact in making a circuit connection.

4. In a flashlight of the character described, a single molded plastic battery casing comprising an elongated tubular body of substantial uniform circular cross-section formed with a closed end bottom and a bulbous hollow hemispherical open end top opposite said bottom, a metallic strip jumper secured to extend lengthwise the interior side of said body and bottom to provide an electrical conductor for connecting with an under terminal of a dry cell battery housed in the casing, the end of said jumper at said open end terminating in a toggle-like switch connecting part formed with an integral spring blade contact adapted to connect said battery in circuit, a rivetted fastening means for rigidly securing said jumper at an inner part of the blade contact to said body, gripper attachment means provided on portion of the jumper end adjoining the blade contact at a spaced distance from said fastening means, an anchorage boss molded on an interior wall of bulbous open end top for engaging with said gripper attachment means, and a toggle-like switch-lever extending through the casing having stub shafts trunnioned on said boss for actuating said blade spring contact in making and breaking a circuit connection, said anchorage boss having an open-ended slot to serve as bearings for trunnioning said stub shafts therein, said gripper attachment means being formed by slitting and bending the end of said jumper to provide an integral spring mounting projecting into said slot for confining the stub shafts therein.

5. In a flashlight of the character described, a single molded plastic battery casing comprising an elongated tubular body of substantial uniform circular cross-section formed with a closed end bottom and a bulbous hollow hemispherical open end top opposite said bottom, a metallic strip jumper secured to extend lengthwise the interior side of said body and bottom to provide an electrical conductor for connecting with an under terminal of a dry cell battery housed in the casing, the end of said jumper at said open end terminating in a toggle-like switch connecting part formed with an integral spring blade contact adapted to connect said battery in circuit, a rivetted fastening means for rigidly securing said jumper at an inner part of the blade contact to said body, gripper attachment means provided on portion of the jumper end adjoining the blade contact at a spaced distance from said fastening means, an anchorage boss molded on an interior wall of bulbous open end top for engaging with said gripper attachment means, a toggle-like switch-lever extending through the casing trunnioned on said boss for actuating said blade spring contact to

deflect the latter in making and breaking a circuit connection, a single molded lens cap removably mounted on said open end top, the sectional thickness of said cap being constructed and arranged to exceed the thickness of the portion of said body attached thereto and to conform the exterior side of the bulbous open end with that of said cap for providing a "tulip" shape head for the flashlight.

6. In a flashlight of the character described, having a single molded plastic battery casing comprising an elongated tubular body of substantial uniform circular cross-section formed with a closed end bottom and a bulbous hollow hemispherical open end top opposite said bottom, a metallic strip jumper secured to extend lengthwise the interior side of said body and bottom to provide an electrical conductor for connecting with an under terminal of a dry cell battery housed in the casing, the end of said jumper at said open end top terminating in a toggle switch connecting part formed with an integral spring blade contact adapted to connect said battery in circuit, a rivetted fastening means for rigidly securing said jumper at an inner part of the blade contact to said body, gripper attachment means provided on portion of the jumper end adjoining the blade contact at a spaced distance from said fastening means, an anchorage boss molded on an interior wall of bulbous open end top for engaging with said gripper attachment means, a toggle-like switch-lever extending through the casing having stub shafts trunnioned on said boss for actuating said blade spring contact in making and breaking a circuit connection, said anchorage boss having open ended slots to serve as bearings for trunnioning said stub shafts therein, said gripper attachment means being formed by slitting and bending the end of said jumper to provide an integral spring mounting projecting into said slot for confining the stub shafts therein, and a single molded lens cap removably mounted on the open end top of greater sectional thickness than that of the adjoining casing, the exterior of said cap forming a continuous surface with that of said open end to provide a "tulip" shape head for the flashlight.

7. A flashlight of the character described, as defined in claim 6, in which a metallic reflector fitted with a lamp is positioned in the bulbous open end top of said body with the open end of the reflector retained by the lens cap and a contact of said lamp connecting with an upper terminal of said battery, said blade contact being constructed and arranged to make and break said circuit connections with the exterior of said reflector on being flexed and unflexed, respectively, by said switch from a normal "off" circuit position.

60 JOSHUA GORDON LIPPINCOTT.
